UNITED STATES PATENT OFFICE.

SAMUEL F. MAXWELL, OF CLIFTON, WEST VIRGINIA.

IMPROVEMENT IN THE MANUFACTURE OF NAIL-KEGS.

Specification forming part of Letters Patent No. **159,945**, dated February 16, 1875; application filed January 16, 1875.

To all whom it may concern:

Be it known that I, SAMUEL F. MAXWELL, of Clifton, in the county of Mason and State of West Virginia, have invented certain Improvements in the Manufacture of Nail-Kegs, of which the following is a full, clear, and exact description, reference being had to the accompanying drawing and the letters of reference marked thereon, making part of this specification, in which—

Figure 1 is a side view of the hoop bender and tacker. Fig. 2 is a top-plan view of Fig. 1.

My invention consists in a peculiar construction of mechanism by means of which I am enabled easily to bend and tack the hoops that are permanently attached to a barrel or keg, as will be more fully hereinafter described.

K is a bench or table, to the side of which is journaled a wheel, K¹. This wheel is made of cast-iron, and formed in two sections, K² K³, the section K³ being less than a semicircle, and is pivoted to the section K² at k. The upper face k¹ of the section K³ is notched or slightly grooved, while at the point k² it is slightly beveled off. m is a catch, which is attached to the face of the section K², and extends over the beveled portion k² of the section K³ when the two sections of the wheel are brought together. m¹ is an eccentric, which works in a recess cut in the face of the section K², and is operated by means of the crank-handle m². To the top of the upright N, attached to the rear of the table K, is fastened a spring-arm,

N¹, while to the bottom of the same upright is attached a treadle, N². The spring-arm N¹ and treadle N² are connected by means of the rod n.

The operation is as follows: The point of the hoop is held under the catch m, and the crank-handle m² so turned as to cause the eccentric m¹ to force up the beveled point k² of the section K³ of the wheel K¹ hard against the end of the hoop. The wheel K¹ is then turned entirely around, the hoop encircling the same, until the catch m passes the point of the spring-arm N¹, when the treadle N² is pressed down by the foot, and causes the spring-arm N¹ to press down upon the hoop. The hoop is then tacked on the notched face k¹, the notches clinching the tacks. The wheel is then turned a quarter back and the hoop loosened.

What I claim as new, and desire to secure by Letters Patent of the United States, is—

Bench K, wheel K¹, constructed in two sections, as described, eccentric m¹, crank-arm m², spring-arm N¹, rod n, and treadle N², the whole constructed and arranged to operate substantially as described.

In testimony whereof I have signed my name to this specification in the presence of two subscribing witnesses.

SAMUEL F. MAXWELL.
